tion, Los Angeles, Calif., a corporation of Calif-
ornia

Application January 7, 1942, Serial No. 425,850

7 Claims. (CL 166—12)

This invention relates to an oil well tool and particularly pertains to a hook wall well packer. In various operations to drill an oil well and to place it on production well packers are used. Some packers which are run into an oil well through a casing are packers of the sleeve type. These may carry means for frictionally engaging the wall of the casing and through the medium of which manipulation of the packer structure from the top of the well will permit the packer to be anchored with relation to the well casing and the deformable packing member to be expanded against the well casing to form a sealed barrier between the packer structure and the casing. In devices of this character there is a relatively small difference in the diameters of the packer sleeve and the well casing. This causes a small annular clearance space to occur between the packer sleeve and the casing while the packer is being lowered, and since the well is usually filled with drilling fluid when the packer structure is lowered into the casing, pressure may be created against the packer sleeve, tending to deform the sleeve and to seat it against the wall of the casing prematurely. It is therefore necessary to lower the packer into the well bore slowly. In order to make it possible for well packers of this type to be lowered into the fluid filled casing rapidly it is desirable to provide an adequate bypass around the packer sleeve and after which the bypass may be closed to make a complete shut-off of fluid through the packer structure, and to then permit the packer to be set. It is the principal object of the present invention, therefore, to provide a well packer structure of the bypass type which is compact in its design and simple in construction, and whereby a maximum amount of drilling fluid may bypass the packer sleeve as the device is lowered into the well and the packer may thereafter be closed and set by a simple and direct operation.

The present invention contemplates the provision of a tubular mandrel suspended from a drill string and upon which a packer structure and a slip cage are carried, said packer structure and mandrel having cooperating valve parts which may be locked in an opened position with relation to each other, the structure being designed to permit the valve cage and its slips to be temporarily anchored with relation to the well casing, the by-pass valve to be closed, and the packer to be set.

The invention is illustrated by way of example in the accompanying drawings in which:

Fig. 1 is a view in elevation showing the completely assembled packer with parts broken away to indicate the bypass valve in its opened position.

Fig. 2—A is an enlarged view in central longitudinal section showing the upper portion of the packer structure and particularly the bypass valve and the packer sleeve in set position.

Fig. 2—B is an enlarged fragmentary view, in longitudinal section showing the lower portion of the packer structure and designating the slips and the slip cone in their set positions.

Fig. 3 is a view in transverse section through the packer as seen on the line 3—3 of Fig. 1 and shows the relative position of the locking sub and the mandrel.

Fig. 4 is a view in transverse section through the packer structure as seen on the line 4—4 of Fig. 2 and shows the relative position of the packer head, the packer sleeve and the tongues of the locking sub.

Fig. 5 is a view in transverse section through the packer structure showing the relationship of the slip cone to the slips.

Fig. 6 is a fragmentary view showing a spring latch for the sub tongue.

Referring more particularly to the drawings, 10 indicates a string of drill pipe or tubing. It will be understood that when this type of packer is used with tubing the well is to be placed on production. When it is used with drill string or tubing it is common practice to mount a well testing tool in conjunction with the packer so that a casing shoe test or production test can be made. The string of pipe 10 is threaded into a suitable coupling 11. The lower end of this coupling has a pin section 12 which is threaded into the box end of a sub 13. A central passageway 14 is formed through the coupling 11 and communicates with an interior bore 15 of the sub. The lower end of the bore 15 communicates with a reduced cylindrical bore 16 which receives the upper end of a tubular packing mandrel 17. Threaded onto the upper end of the mandrel and within the bore 16 is a nut 18 by which a suitable packing ring 19 is held so that it will form a fluid-tight seal between the wall of the bore 16 and the mandrel 17. The lower end of the sub 13 is fitted with a conical valve face 20 which is complementary to a tapered valve seat 21 carried by the packer head 22. A relatively large central cylindrical bore 23 extends downwardly through the packer supporting head 22. This bore also accommodates a tubular metallic supporting sleeve 24 and the tubular mandrel 17.

The diameters of these parts are such as to insure a relatively large annular bypass space 25 at the upper end of the packer head and a bypass space 26 which occurs between the supporting sleeve 24 and the mandrel. The supporting sleeve 24 fits into the bore of the packer head 22 with a sliding fit and is held against rotation by a pin 27 which projects into a longitudinal slot 28 of the supporting sleeve and is threaded through the wall of the packer head 22. The lower end of the supporting sleeve 24 is threaded into a packer collar 29. The upper end of this collar is fitted with a suitable shoulder 30 against which a packer sleeve structure 31 may rest. A similar shoulder 32 is provided at the lower end of the packer head 22 and rests against the upper end of the packer sleeve structure 31. It is to be understood that the packer sleeve structure 31 may be in the form of a continuous cylindrical rubber sleeve or may constitute a plurality of separate packing rings formed of rubber or other suitable deformable packing material. In any event the inner surface 33 of the packer sleeve 31 fits snugly around the supporting sleeve 24 and when longitudinally compressed will distend to form a seal with a well casing 34. Formed integral with the packer collar 29 is a slip expanding cone 35. This slip expanding cone is screwed onto the lower end of the mandrel section 17 and thus fixes the cone relative to the mandrel as well as the packer collar 29 and the packer supporting sleeve 24. Extending longitudinally of the outer tapered face of the cone 35 are undercut ways 36 which receive the dovetailed ribs 37 of wickered slips 38. These slips move along the ways 36 as the expanding cone 35 moves downwardly in unison with the mandrel. The lower end of each of the slips 38 is formed with a slot 39 to receive the upper end of a link 40. The upper end of the link is pivoted in the slot to a transverse pivot pin 41. The lower end of each of the links 40 extends between lugs 42 carried upon a ring 43 and is pivotally connected by a pin 44. The ring 43 fits within an annular groove 45 formed in the outer face of the upper collar 46 of a slip cage 47. The slip cage 47 includes a cylindrical sleeve 48 extending downwardly and terminating in a collar 49 at its lower end. The collars 46 and 49 each have a central bore having a sliding fit with relation to the lower mandrel extension 17'. Formed through the walls of the sleeve portion 48 of the slip cage are J-slots 50. The upper end of each J-slot is formed with a lateral recess providing a lock shoulder 51. Secured to the mandrel section 17' by pins 52 are lock lugs 53 which when engaging the shoulder 51 prevent relative longitudinal movement of the cage 47 with relation to the mandrel section 17'. Bolting pads are formed on the collar 49 of the cage 47 and receive cap screws 54 which hold bow springs 55 in position. These springs extend longitudinally of the cage 47 and their upper free ends are slidably held in longitudinal slots 56 of the upper collar 46.

The valve face 28 of the sub 13 is held in its opened and spaced position relative to the valve seat 21 by engagement of tongues 57 with the upper end of the packer supporting sleeve 24. The tongues 57 are formed integral with the sub 13 and extend downwardly into the opened end of the packer head. These tongues are relatively narrow in width and arcuate in section so that their inner faces conform to the outer circumference of the mandrel 17 and their outer

faces substantially conform to the circumferential face of the bore 23. The lower ends of the tongues are semicircular and bear against an end face 58 which extends transversely of the end 60 of the packer supporting sleeve 24 and parallel thereto. One end of each of the faces 58 terminates in an arcuate shoulder 61. The other end of each of the faces 58 has a downwardly curved arcuate portion 62 which adjoins a longitudinally extending face 63 of a slot 64. The slot 64 is cut longitudinally of the supporting sleeve 24 and is of a length greater than the length of the tongue 57 which is to extend into it. The slot 64 has a wall 65 parallel to the wall 63 and spaced therefrom a distance to accommodate the width of the tongue 57 which is to extend into it. Thus when the tongue 57 is in position within the slot 64 the supporting sleeve 24 will be held against rotation with relation to the sub 13 and while the tongue 57 is out of register with the slot 64 the valve element 28 will be supported in spaced relation to the valve seat 21 and will permit free circulation of fluid through the packer head 22, the supporting sleeve 24, and through bypass openings 66 which are formed in the cone 35.

In operation of the present invention the structure is assembled as shown in the drawings, and prior to lowering the packer into the well the slip cage 47 is rotated with relation to the tubular mandrel section 17' and the lugs 42 are seated within the recess defined by the shoulder 51 of the J-slots 50. When the slip cage 47 is in this position the slips 38 will be retracted in the ways 36 upon the cone 35 and will be in their contracted position with relation to the well casing 34 so that they will not engage the casing while the bow springs 55 yieldingly and frictionally engage the casing. At the same time the sub 13 will be rotated with relation to the mandrel 17 and the packer supporting sleeve 24 so that the ends of the tongues 57 will substantially rest against the shoulder faces 58 of the supporting sleeve 24 and will be rotated against the stop shoulders 61. It is to be understood that one or more of the tongues 57 are provided, although in the drawings two are shown. In the event that there is a tendency for relative rotation between the hub 13 and the supporting sleeve 24 the shoulders 58 are fitted with a leaf spring element 68, as shown in Fig. 6 of the drawing. This will tend to hold the tongues yieldably in position so that they cannot move to register with the longitudinal slots 64 accidentally. At this time the packer sleeve unit 31 is in its normal non-expanded position, and thus provides clearance with relation to the casing 34. The structure thus set is lowered into the well. When the packer reaches a point at which it is to be set the string of pipe 10 is rotated in a direction to move the lugs 42 along the shoulders 51 of the J-slots 50 to a point in register with the longitudinal portion of these slots while the slip sleeve 47 is held against rotation by the bow springs 55. When this degree of rotation has taken place the string of pipe 10 is lowered with the coupling 11 and the sub 13. The sub 13 will then transmit an end thrust upon the supporting sleeve 24 by means of the tongues 57. This will tend to force the supporting sleeve 24 downwardly together with the lower packing collar 29, the mandrel sections 17 and 17', and the slip cone 35. The result will be that the cone 35 will force itself downwardly along the slips 38 to move the slips outwardly into positive engagement with

the casing 34, and at the same time the lock lugs 53 will move down the longitudinal lengths of the bayonet slots 50.

During the foregoing operation the packer mandrel, the cone and the entire packer structure, including the packer head 22, move downwardly as a unit with relation to the slip cage 41. It is then desirable to release the sub 13 with relation to the supporting sleeve 24. This is done by rotating the string of pipe 10 and the sub 13 in the direction of the arrow *a* until the tongue 57 strikes the face 65 of the slot 64. When this is accomplished the drill string may be lowered, with the result that the tongue 57 will travel downwardly along the slot 64 until the conical valve element 20 of the sub rests against the valve seat 21 and interrupts the bypass of fluid through the passageways 66, the annular space 26 through the supporting sleeve 24, and the space 25 in the packer head 22. After the member 20 is seated upon the valve seat 21 additional weight may be imposed upon the sub 13 to exert a pressure on the packer sleeve unit 31 and to distend the packer into sealing relationship with the casing 34 into which it has been lowered. Attention is directed to the fact that when the slips have been set the sub 13 may move with relation to the mandrel section 17 as the head, comprising the nut 18, moves in the cylindrical bore 15 of the sub. Thus, the bypass valve may be opened and closed at will without affecting the packer.

When it is desired to remove the packer from the well bore an upward pull is made on the string of pipe 10. This will lift the sub 13 until its shoulder 69 engages the packing 19 or the shoulder formed by the nut 18. Prior to the time of the engagement of these shoulders the tongues 51 will have been withdrawn from the slots 64 so that the sub may be rotated to move the tongues into abutting relation to the shoulders 58. Continued upward movement of the sub will cause the mandrel 17 and the cone 35 to raise, and at the same time retract the slips 38 so that they will become disengaged from the casing. This action will also produce relative movement of the slip cage with relation to the lugs 53 so that the structure may be rotated to re-lock the slip cage 41 with relation to the mandrel section 17 and make it possible to move the packer to any other desired position and re-set it.

It will thus be seen that by the use of the packer structure here disclosed a maximum effective bypass passageway will be provided around the packer element, and that the bypass may be closed and opened, the packer set and released by the use of a simple and compact structure, and by easy manipulation of the drill string.

While I have shown the preferred form of my invention as now known to me, it will be understood that various changes may be made in combination, construction and arrangement of parts by those skilled in the art without departing from the spirit of my invention as claimed.

Having thus described my invention, what I claim and desire to secure by Letters Patent is:

1. A well packer adapted to be supported upon a string of pipe and to be lowered into a well, said packer comprising a sub, a mandrel extending downwardly therefrom and being supported thereby for limited relative longitudinal movement, a fixed cone on the mandrel, a slip cage slidable upon the mandrel and carrying yield-

able means engaging a well casing wall, a bayonet type lock between the slip cage and the mandrel temporarily holding said parts against relative longitudinal movement, slips articulately connected to the slip cage and interlocking with the tapered face of the slip cone to move longitudinally thereof to and from casing engaging positions, a packer collar fixed to the upper end of the expanding cone, said cone having wall ports through it beneath the collar, a supporting sleeve fixed to said collar and through which the mandrel extends, said supporting sleeve and collar being of a diameter sufficiently larger than the mandrel to provide an annular passageway communicating with said ports, a packer head slidable upon the upper end of said supporting sleeve means holding said supporting sleeve against rotation with relation thereto, said packer head having a central passageway therethrough above the supporting sleeve and communicating therewith, a valve seat formed on the upper edge of said packer head and communicating with the passageway, a valve element formed on the lower end of the sub and adapted to form a seal with the seat on the packer head when bearing thereagainst, and cooperating means between the sub and the supporting sleeve whereby said valve elements may be maintained in an open position while the well packer is being lowered into the well and the slips are set and releasably acting thereafter upon rotation of the sub relative to the supporting sleeve to permit the valve seat of the sub to move down onto the valve seat on the packer head and to thereafter impose pressure upon the packer head to expand the packer.

2. A bypass well packer of the hook wall type adapted to be supported by a string of pipe, a sub secured to the lower end of said string of pipe, a mandrel suspended thereby and extending downwardly therefrom, said mandrel and sub having relative longitudinal movement with relation to each other, a slip expanding cone secured rigidly upon the mandrel, a packer collar formed at the upper end of said cone and being rigid therewith, said collar having a central bore materially greater in diameter than the outside diameter of the mandrel, the structure including the collar and the cone having a fluid chamber therein circumscribing the mandrel, ports in the cone establishing communication between said fluid chamber and the well bore, a supporting sleeve secured to the collar and through which the mandrel extends, said supporting sleeve being of an internal diameter materially greater than the external diameter of the mandrel, whereby an annular unrestricted fluid passageway will be formed in communication with said fluid chamber, a deformable packer unit mounted upon the supporting sleeve and resting against the packer collar shoulder, a packer head slidably mounted upon the upper end of said supporting sleeve and having a shoulder resting against the upper end of the packer sleeve, means preventing relative rotation between the packer head and the supporting sleeve, said head being of sufficient length to accommodate the supporting sleeve when the packer unit is compressed, the upper end of said packer head being open and establishing communication with the annular bypass space within the sleeve, a valve seat formed around and upon the upper open end of the packer head, a valve seat formed upon the end of the sub and adapted to seal said opening when

resting against the seat upon the packer head, a slip structure carried by the mandrel and actuated by the slip cone, tongues formed integral with the sub and extending downwardly along the mandrel and into the open end of said packer head, shoulder faces on the end of the supporting sleeve to be engaged by the ends of said tongues to thereby hold the mandrel, the packer cone, the packer unit and the packer head in their outermost positions with relation to the sub, whereby all of said elements may move in unison with the sub, and release slots in the supporting sleeve into which said tongues may move to permit relative movement between the mandrel and the sub and to allow the valve seat on the sub to engage the valve seat on the packer head and close the same.

3. The structure of claim 2 in which said releasing action is brought about by rotation of the sub with relation to the supporting sleeve, limiting stops carried by the supporting sleeve and engaged by said tongues to limit the degree of rotation of the sub and the supporting sleeve, and cooperating latch means between the mandrel and the slip structure, whereby said latch means may be released when the tongues are in engagement with said limiting stops.

4. The structure of claim 2 in which said releasing action is brought about by rotation of the sub with relation to the supporting sleeve, limiting stops carried by the supporting sleeve and engaged by said tongues to limit the degree of rotation of the sub and the supporting sleeve, cooperating latch means between the mandrel and the slip structure, whereby said latch means may be released when the tongues are in engagement with said limiting stops, and means yieldably holding said sub and supporting sleeve against relative rotation.

5. A packer structure adapted to be suspended from a string of pipe and comprising a tubular sub having a bore at the lower end thereof and a counterbore within the tubular sub and above said bore, a mandrel extending downwardly through said bore, a head on the mandrel having limited longitudinal movement within said counterbore, a shoulder within the sub against which the head may rest in its lowermost position, an expanding cone fixed upon said mandrel at a point intermediate its length and having an outer face formed with dovetailed grooves, slips engaging said dovetailed grooves and sliding longitudinally of the cone to set and retracted positions, a slip cage, said cage on said mandrel including springs for frictionally engaging a casting into which the structure is lowered, articulate connections between the slip cage and the slips, a packer collar formed integral with the upper enlarged end of the slip cone and having a central threaded bore materially greater in diameter than the outside diameter of the mandrel, a supporting sleeve threaded into said bore and extending upwardly therefrom to form an annular bypass space around the mandrel, ports formed in the expanding cone below the packer collar and in communication with said space, a cylindrical packer head telescoping over said supporting sleeve and longitudinally movable thereon, means preventing rotation and permitting limited longitudinal movement of said head with relation to the supporting sleeve, a packer collar carried by said supporting sleeve, a deformable packer unit circumscribing the supporting sleeve and being disposed between the packer head and collar, an annular valve seat

formed on the upper end of the packer head and around the mandrel, a valve element carried by the sub adapted to engage with said seat, and lock means normally holding said valve passageway open and acting to permit closing of said valve passageway upon rotation of the supporting string of pipe.

6. A well packer, comprising a tubular mandrel, an expanding cone fixed thereto at a point intermediate the ends thereof, slips slideable upon said expanding cone to engage well casing, a slip cage slidably mounted upon the mandrel, locking means for temporarily locking the cage and the slips with relation to the mandrel and whereby manipulation of the mandrel will release the cage and the slips to permit the cone to move the slips, a packing collar carried on the upper end of the slip cone, a supporting sleeve attached to the collar and extending upwardly around the mandrel and forming an annular space between the sleeve and the mandrel, a deformable packing sleeve resting upon the packing collar and embracing the supporting sleeve, ports through the cone to establish communication between the well casing and the annular space within the supporting sleeve, a packer head resting upon the upper edge of the packer sleeve and slidably mounted on the upper end of the supporting sleeve, means permitting limited longitudinal movement between the packer head and the supporting sleeve, a valve seat formed on the upper face of the packer head and providing an opening communicating with the interior of the supporting sleeve, a sub carried upon a supporting string of pipe and formed at its lower end with a valve face complementary to the valve seat on the packer head, means connecting the upper end of the mandrel with the sub for a limited relative longitudinal movement between the mandrel and the sub, cooperating means between the sub and the supporting sleeve whereby the slips may be set and released, and cooperating means between the sub and the supporting sleeve whereby the packer may be set and released.

7. A bypass well packer of the hook wall type adapted to be supported by a string of pipe, a sub secured to the lower end of said string of pipe, a mandrel suspended thereby and extending downwardly therefrom, said mandrel and sub having relative longitudinal movement with relation to each other, a slip expanding cone secured rigidly upon the mandrel, a packer collar formed at the upper end of said cone and being rigid therewith, said collar having a central bore materially greater in diameter than the outside diameter of the mandrel, the structure including the collar and the cone having a fluid chamber therein circumscribing the mandrel, ports in the cone establishing communication between said fluid chamber and the well bore, a supporting sleeve secured to the collar and through which the mandrel extends, said supporting sleeve being of an internal diameter materially greater than the external diameter of the mandrel, whereby an annular unrestricted fluid passageway will be formed in communication with said fluid chamber, a deformable packer unit mounted upon the supporting sleeve and resting against the packer collar shoulder, a packer head slidably mounted upon the upper end of said supporting sleeve and having a shoulder resting against the upper end of the packer sleeve, means preventing relative rotation between the packer head and the supporting sleeve, said head being

of sufficient length to accommodate the supporting sleeve when the packer unit is compressed, the upper end of said packer head being open and establishing communication with the annular bypass space within the sleeve, a valve seat formed around and upon the upper open end of the packer head, a valve seat formed upon the end of the sub and adapted to seal said opening when resting against the seat upon the packer head, a slip structure carried by the mandrel and actuated by the slip cone, tongues formed integral with the sub and extending downwardly along the mandrel and into the open end of said packer head, shoulder faces on the end of the supporting sleeve to be engaged by the ends of said tongues to thereby hold the mandrel, the packer cone, the packer unit and

the packer head in their outermost positions with relation to the sub, whereby all of said elements may move in unison with the sub, release slots in the supporting sleeve into which 5 said tongues may move to permit relative movement between the mandrel and the sub and to allow the valve seat on the sub to engage the valve seat on the packer head and close the same, said releasing action being brought about 10 by rotation of the sub and its tongues with relation to the release slots on the supporting sleeve, and limiting stops associated with the release slots and carried by the supporting sleeve and engaged by said tongues to limit the degree of 15 rotation of the sub and the supporting sleeve.

JOHN T. PHIPPS.
